(57) **CLAIM**

The ornamental design for a vehicle taillamp, as shown and described.

DESCRIPTION

FIG. 1 is a front and left side perspective view of a vehicle taillamp showing my new design;

FIG. 2 is a front elevation view of the vehicle taillamp of FIG. 1;

FIG. 3 is a left side elevation view thereof;

FIG. 4 is a right side elevation view thereof;

FIG. 5 is a back elevation view thereof;

FIG. 6 is a top plan view thereof; and,

FIG. 7 is a bottom plan view thereof.

The broken lines in the drawings depict portions of the vehicle taillamp that form no part of the claimed design. The mirror image of the vehicle taillamp is claimed, but not shown.
